US00D886821S

(12) **United States Design Patent** (10) **Patent No.:** **US D886,821 S**
Escolin et al. (45) **Date of Patent:** **** Jun. 9, 2020**

(54) **COMBINED COMPUTER AND DOCKING MOUNT**

(71) Applicant: **Microsoft Corporation**, Redmond, WA (US)

(72) Inventors: **Timothy G. Escolin**, Seattle, WA (US); **Ryan Eugene Whitaker**, Seattle, WA (US); **Young Soo Kim**, Bellevue, WA (US); **Jonne Aapi Harju**, Seattle, WA (US); **Kae-Ling J. Gurr**, Seattle, WA (US)

(73) Assignee: **Microsoft Corporation**, Redmond, WA (US)

(**) Term: **15 Years**

(21) Appl. No.: **29/647,800**

(22) Filed: **May 15, 2018**

(51) LOC (12) Cl. **14-02**

(52) U.S. Cl.

USPC **D14/375**; D19/114; D14/336

CLAIM

The ornamental design for a combined computer and docking mount, as shown and described.

DESCRIPTION

FIG. 1 is a front perspective view of a combined computer and docking mount showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

The broken lines in the drawings depict portions of the combined computer and docking mount that form no part of the claimed design.
